[57] CLAIM

The ornamental design for a combined cue protector and tip scuffer, as shown and described.

DESCRIPTION

FIG. 1 is an elevational view showing my new design for a combined cue protector and tip scuffer as attached to the handle section of a cue stick shown in phantom lines for illustrative purposes only; the cue protector and tip scuffer is symmetrical about its longitudinal axis so that top, bottom and both side views would be similar;

FIG. 2 is a left end elevational view thereof;

FIG. 3 is a right end elevational view thereof; and

FIG. 4 is a longitudinal sectional view taken along lines 4—4 on FIG. 2 showing the configuration of the interior, which is exposed from the right end.

FIG. 1.

FIG. 2.

FIG. 3.

FIG. 4.
